UNITED STATES PATENT OFFICE.

JULES RICHARD AND RENÉ PIERRE MARIE LAVIE, OF PARIS, FRANCE.

PHOTOGRAPHIC-ROLL HOLDER.

1,155,508.

Specification of Letters Patent.

Patented Oct. 5, 1915.

Application filed January 11, 1913. Serial No. 741,515.

To all whom it may concern:

Be it known that we, JULES RICHARD, of 25 Rue Mélingue, in the city of Paris, Republic of France, manufacturer of optical instruments, and RENÉ PIERRE MARIE LAVIE, of 16 Rue du Faubourg Saint-Denis, in the city of Paris, Republic of France, doctor of medicine, have invented Improvements in Photographic-Roll Holders, of which the following is a full, clear, and exact description.

It is known that photographic films are highly sensitive to variation in temperature and in hygrometric conditions, thus for example, they become hollow under the influence of the dryness of the air and arched under the influence of moisture. It follows that these films present the inconveniences of not lying perfectly flat in the focal plane of the photographic apparatus. Even in the case of a well stretched film it forms more or less accentuated undulations. In these conditions, every point of the portion of the film that is to be exposed is not exactly located in the focal plane. This defect is not of great importance in ordinary photographic apparatus provided with long focus lenses and which furnish photographs intended to be viewed directly, or even in cinematographs in which the film is replaced with sufficient rapidity not to afford it the time to be influenced by external physical agents such as heat and humidity. This is not the case, however, with verascopes, the objectives of which are of short focal length, since a slight undulation of the film is sufficient to produce cloudy patches in the image. This defect is increasingly serious if the pictures are intended to be examined with magnifying glasses. With verascopes, therefore, it is important that the film should be held flat and exactly in the focal plane while taking the photographs. The present invention permits of obtaining this result in an exceedingly simple manner. It is broadly characterized by the fact that at the proper moment the film is pressed against a fixed glass with parallel faces, arranged on the same side as the objectives, by means of a movable plate which can be brought toward

and separated from the glass, this movement being controlled by special mechanism.

The novel device is completed by a safety device which prevents the film from being advanced when it is pressed against the glass.

The invention is illustrated by way of example only in the accompanying drawings in which:

Figure 1 is a plan view of the improved roll holder; Fig. 2 is a similar view, the parts occupying a different position; Fig. 3 is a view made by looking in the direction of the arrows, Fig. 1; Fig. 4 is a section made on line A—A of Fig. 3; Fig. 5 is a section made on line B—B of Fig. 4; Fig. 6 is a section made on line C—C of Fig. 1; Figs. 7 and 8 are left hand and right hand views of the apparatus; Fig. 9 is a view similar to Fig. 8. Fig. 10 is a section on line D—D of Fig. 8 with certain parts shown in a different position. Fig. 11 is a section similar to Fig. 4, showing the operation; Fig. 12 is a back view of the roll holder, the cover being removed.

As illustrated in the drawing, a roll holder constituted by a box *a*, parallelepiped in form, is mounted on the verascope *b* (Fig. 1) in place of the ordinary slide containing the plates, with this object the said box is provided with ribs *a*¹ (Fig. 7) intended to engage in grooves in the verascope. The roll holder is closed by a cover *c* which is readily detachable and held in place by pins *a*² on the body of the roll holder (Fig. 8) which engage in corresponding holes in the cover and by pins *c*¹ on the cover, upon which leaf springs *d* engage (Figs. 4 and 7).

In order to remove the cover, it is only necessary to separate the springs *d* whereupon the cover can be removed by displacing it slightly to the right. In this roll holder a supply spool *e* from which the film is unwound and a spool *f* onto which the film is wound are arranged. Each of these spools is carried in the ordinary manner, by a nipple *g*, and a plate *h* (Fig. 6). This plate *h* is integral with a rod *h*¹ and a milled knob *j*, which permits of rotating it. A spring *j*¹ housed in a fixed box *k* mounted upon the

roll holder, and bearing upon the bottom of this box on the one hand and on the other hand against a disk l integral with the tapet presses this plate h toward the interior 5 of the roll holder.

The film y unwinding from the spool e passes over rollers m , m^1 and m^2 (Fig. 4). The film is located between the rollers m and m^1 and also between a glass o with parallel faces and a plate p . A guide m^3 (Fig. 4) serves to facilitate the introduction of the band. The glass rests upon slide ways o^2 (Figs. 5 and 10). To facilitate fitting and removing it, the roll holder is provided with 15 a small shutter g (Figs. 8 to 10) pivoted at g^1 . Fig. 8 shows this shutter closed and Figs. 9 and 10 illustrate the same open. It is held closed by small bolts g^2 which can be operated by means of pins g^3 (Fig. 8). 20 The aforesaid plate p can be brought toward or separated from the glass o by means of a cam control device. The plate carries two angle pieces r (Fig. 5) forming slides in fixed slideways integral with the box of the 25 roll holder. Each of these angle pieces is cut as shown in Fig. 4 in such a manner as to form a housing r^1 for a cam s . The two cams s are keyed upon a shaft t provided with a handle t^1 for the purpose of rotating 30 it. In the position illustrated in Figs. 1 and 4 the plate p is separated from the glass o . In this position, the film y is able to slide between the plate and the glass so that the exposed portion of the film can be wound up 35 and an unexposed length substituted therefor.

In order to bring the plate p and the glass o together, the handle t^1 is rotated through a quarter turn in a clockwise direction, the 40 cams s displace the plate p which applies the film to the glass (position illustrated in Figs. 2 and 11) while preventing this film from forming undulations. The film being thus perfectly plane the photograph is absolutely 45 clear. In order to prevent attempts to displace the film while it is clamped between the plate and the glass, the apparatus comprises special safety means.

The disk l of the support for the winding 50 spool is serrated upon its periphery and forms a ratchet. A spring pawl u (Figs. 1 and 6) is in mesh with this ratchet and only permits the rotation of the operating handle in the direction for winding the film upon 55 this spool. This pawl can be blocked by a bolt v (Fig. 1) controlled by a cam keyed upon the shaft t .

In the drawing has been illustrated a cam v^1 (Fig. 2) engaged in a housing having a 60 profile suited to that of the bolt. In the position illustrated in Fig. 1, in which the plate p is separated from the glass, the bolt is removed from the pawl, so that the handle j may be rotated. On the contrary, in the

position illustrated in Fig. 2, in which the plate p is brought toward the glass, the pawl and the handle j are locked. The bolt u presents an opening z and an index z^1 indicating whether the film is freely held. 70

Claims:

1. In a photographic apparatus, the combination of a fixed glass plate, a movable table, a supply spool, a winding spool adapted to take up a film passing between said glass plate and table from said supply spool, an operating handle for controlling the shifting of the table against said glass plate, and means actuated by the operation of said handle for locking the winding spool when the film is clamped between said table and 80 glass plate. 75

2. In a photographic apparatus, the combination of a fixed glass, a movable table, a supply spool, a winding spool adapted to take up a film passing between said glass 85 and table from said supply spool, an operating handle for controlling the shifting of the table against said glass, and a bolt actuated by the operation of said handle for locking the winding spool when the film is clamped 90 between said table and glass. 95

3. In a photographic apparatus, the combination of a fixed glass, a movable table, a supply spool, a winding spool adapted to take up a film passing between said glass 95 and table from said supply spool, an operating handle for controlling the shifting of the table against said glass, a bolt actuated by the operation of said handle, a ratchet for said winding spool and a pawl engaging 100 with said ratchet and adapted to be locked by said bolt when the film is clamped between said table and glass. 105

4. In a photographic apparatus, the combination of a fixed glass, a movable table, a supply spool, a winding spool adapted to take up a film passing between said glass and table from said supply spool, an operating handle for controlling the shifting of the table against said glass, a bolt actuated 110 by the operation of said handle, a ratchet for said winding spool, a pawl engaging with said ratchet and adapted to be locked by said bolt when the film is clamped between said table and glass, and means to indicate whether the film is in a free or clamped position. 115

5. In a photographic apparatus, the combination of a fixed glass, a movable table, a supply spool, a winding spool adapted to 120 take up a film passing between said glass and table from said supply spool, a cam shaft provided with an operating handle and adapted by its engagement with the table to shift said table against the glass so as to clamp the film therebetween, a ratchet for the winding spool, a pawl in engagement with said ratchet, a bolt member controlled 125

by said cam shaft and adapted to lock said pawl so as to prevent further rotation of said ratchet when the film is thus clamped, an index actuated by said bolt and adapted 5 to indicate whether the film is in a free or clamped position, substantially as herein described.

The foregoing specification of our im-

provements in verascopes, signed by us this 23rd day of December 1912.
